(57) **CLAIM**

The ornamental design for a bag, as shown and described.

DESCRIPTION

1. Bag

- 1.1: A front perspective view of a design of a bag.
1.2: A back perspective view of the design of the bag of Reproduction 1.1.
1.3: A bottom perspective view of the design of the bag of Reproduction 1.1.
1.4: A top perspective view of the design of the bag of Reproduction 1.1.
1.5: Another front perspective view of the design of the bag of Reproduction 1.1.
1.6: A right perspective view of the design of the bag of Reproduction 1.1.
1.7: A left perspective view of the design of the bag of Reproduction 1.1.
Reproduction 1.2 shows the back of the bag in Reproduction 1.1 at an alternate perspective view from Reproduction 1.1. Reproductions 1.3 and 1.4 show the bottom and top of the back featuring the claimed design at alternate perspective views from the remaining Reproductions.

1 Claim, 7 Drawing Sheets(56)
